UNITED STATES PATENT OFFICE.

HOWARD J. D. MONTEITH, OF TRENTON, NEW JERSEY.

DESIGN FOR A WALL LIGHTING FIXTURE.

Application filed November 8, 1923. Serial No. 7,720. Term of patent 14 years.

To all whom it may concern:

Be it known that I, HOWARD J. D. MONTEITH, a subject of the King of Great Britain, and a resident of Trenton, in the county of Mercer and State of New Jersey, United States of America, have invented a new, original, and ornamental Design for a Wall Lighting Fixture, of which the following is a specification, reference being had to the accompanying drawings, forming part thereof.

Fig. 2 is a side view thereof.

Fig. 3 is a rear view of the same.

Fig. 4 is a top plan view.

Fig. 5 is a bottom plan view.

I claim:

The ornamental design for a wall lighting fixture, as shown.

HOWARD J. D. MONTEITH.
